(57) **CLAIM**

The ornamental design for a tire puncturing device, as shown and described.

DESCRIPTION

FIG. 1 is a perspective view of a tire puncturing device; FIG. 2 is a front elevational view thereof, the rear elevational view being a mirror image; FIG. 3 is a right-side elevational view thereof, the left-side elevational view being a mirror image; FIG. 4 is a top plan view thereof; FIG. 5 is a bottom plan view thereof; FIG. 6 is a bottom perspective view of the ring platform, showing the concave structure underneath; FIG. 7 is a bottom perspective view of the hollowed spike, showing that it is hollow down through the base; FIG. 8 is a side elevational view of a weapon platform and weapon deployed in the upright position; and, FIG. 9 is a side elevational view of a weapon platform and weapon deployed in the side position, showing that the base is loose to allow for an angle of about 30 degrees. The broken line showing of a picture in FIG. 8 and FIG. 9 is included for the purpose of showing environmental structure and forms no part of the claimed design.

1 Claim, 9 Drawing Sheets
